UNITED STATES PATENT OFFICE.

CLARENCE W. HAZELETT, OF LAKEWOOD, OHIO, ASSIGNOR TO NATIONAL CARBON COMPANY, INC., A CORPORATION OF NEW YORK.

STORAGE-BATTERY-FILLING VENT.

1,316,035.

Specification of Letters Patent. Patented Sept. 16, 1919.

Application filed February 20, 1918. Serial No. 218,366.

To all whom it may concern:

Be it known that I, CLARENCE W. HAZELETT, a citizen of the United States, residing at Lakewood, in the county of Cuyahoga and State of Ohio, have invented a certain new and useful Improvement in Storage-Battery-Filling Vents, of which the following is a full, clear, and exact description.

10 This invention relates to electric batteries and is a continuation of my application filed September 23, 1916, Serial No. 121,720.

15 It is common practice to incase storage battery elements in rubber jars and to inclose the top with an appropriate cover such as hard rubber which usually is sealed in with pitch or bituminous material. It is necessary to add electrolyte or water to the 20 cell, from time to time, and therefore a removable stopper or closure is provided which usually consists of a vent plug threaded into the cover. It is considerable trouble to thread and unthread the removable 25 vent plug, as a number of revolutions are necessary to complete the operation. Also the threads are liable to be jammed or stripped by careless insertion of the plug. That is, if the plug is not held exactly central with the threaded hole it will screw 30 into the cover with the threads crossed and not in perfect mesh, because the material of the cover and plug are sufficiently soft to permit this. My invention aims to 35 overcome these and other difficulties.

Referring to the drawings:

Figure 1 is a sectional elevation of a battery containing my improved vent plug.

Fig. 2 is a bottom view of a section of the 40 cover shown in Fig. 1, with the vent plug in closed position.

Fig. 3 is an elevation of the portion of the cover shown in Fig. 2, looking in the direction of arrow B.

45 Fig. 4 is an elevation of the portion of the cover shown in Fig. 2, looking in the direction of arrow A.

Fig. 5 is an elevation of the vent plug taken in the direction of arrow B of Fig. 2.

50 In the drawings the usual jar 1 is shown inclosing the component parts of the cell with which the cover 2 coöperates to retain the parts in position. The specific form of the cover is not of importance as far as this 55 invention is concerned, and only the part

coöperating with the vent plug is shown in Figs. 2 and 3. In these figures the cover 2 has arcuate cam surfaces 3 and 4 on the underside, which coöperate with arms 5 and 6 on a vent plug 8 to close the filling opening 8' in the cover 2.

The vent plug has wings 9 and 10 preferably arranged in parallel direction with the arms 5 and 6, to permit ready insertion of the plug through the hole 8' which is provided with slots 11 and 12 to receive the arms 5 and 6 which preferably have cam surfaces fitting the cam surfaces 3 and 4. The slots 11 and 12 are located at the foot of the arcuate cam surfaces 3 and 4 so that, 70 when the plug is inserted through a washer 13 of soft rubber or other appropriate material, and the cover 2, a turning movement will cause the arms 5 and 6 to ride up cams 3 and 4 substantially onto the surfaces 14, 75 15, against the abutments 16, 17, which prevent further movement in that direction. Due to the action of the arms of the plug on the cam surfaces, elastic washer 13 is compressed to form a tight seal which prevents the escape of electrolyte.

The vent plug has a hole 18 extending from the bottom to a point adjacent the top of the plug where it branches into one or more channels 19 leading to the exterior 85 of the plug at an angle to the hole 18. These channels permit the escape of gas from the interior of the cell which is necessary to prevent the disrupting of the container by pressure of accumulating gases. 90

With my improvement it is not necessary to use care in inserting or removing the vent plug, as there are no threads to jam and it is impossible to perform an incorrect manipulation. Since the wings 9 and 10 are in line with the arms on the bottom of the plug, the insertion of the plug through the cover can be readily made, and a quick turn in a clockwise direction accomplishes the removal in the same expeditious manner. 95 The abutments 16 and 17 on the cover extend to the slots 12 and 11 respectively, which prevents the plug being rotated in the wrong direction when attempting to seat it in position in the cover.

Having described my invention, what I claim is:

1. In storage batteries, a cover having a filling opening, a slot joining said opening, an arcuate cam surface commencing at said 110

- slot and inclining away from said cover, a plug adapted to pass through said slot and having an arm adapted to ride up said cam surface during the rotation of the plug in said opening, and means on said plug adapted to be forced against the cover by the action of the arm on said cam.
2. In storage batteries, a cover having a filling opening, a slot joining said opening, an arcuate cam surface beneath the cover commencing at said slot and inclining away from the cover, said cam terminating in means to hold the said plug against further rotative movement.
10. 3. In storage batteries, a cover having a filling opening, said opening consisting of a circular portion and a slot having sides extending from the circular portion, a thickened cam portion projecting from the under surface of the cover and extending from one side of the slot radially around the circular portion of the opening, a flanged plug adapted to be inserted in the opening, an elastic washer between the flange of the plug and the cover, and an arm on said plug adapted to ride up the cam onto said surface to compress the elastic washer and seal the battery.
15. 4. In storage batteries, a cover having a filling opening, said opening consisting of a central portion and a pair of oppositely disposed slots extending from the central portion, a pair of thickened cam portions projecting from the lower surface of said cover and extending radially around the portions of the circular opening between the slots, a flanged plug adapted to be inserted in said opening, an elastic washer between the flange of the plug and said cover, arms on said plug adapted to pass through the slots and to ride up the cams onto the surfaces to compress the elastic washer against the cover, abutments adjacent said surfaces to prevent further rotative movement of the plug, and means to prevent the arms from being rotated away from said cams when in line with said slots.
20. 5. In storage batteries, a cover having a filling opening, said opening consisting of a circular portion and a pair of oppositely disposed slots extending from the circular portion, a pair of thickened cam portions projecting from the lower surface of said cover and extending radially around the portions of the circular opening between the slots, a flanged plug adapted to be inserted in said opening, an elastic washer between the flange of the plug and said cover, arms on said plug adapted to pass through the slots and to ride up the cams onto the surfaces to compress the elastic washer against the cover, abutments adjacent said surfaces to prevent further rotative movement of the plug, and means to prevent the arms from being rotated away from said cams when in line with said slots.
25. 6. In storage batteries, a cover having a filling opening, said opening consisting of a central portion and a pair of oppositely disposed slots extending from the central portion, a pair of thickened cam portions projecting from the lower surface of said cover and extending radially around the portions of the circular opening between the slots, a flanged plug adapted to be inserted in said opening, an elastic washer between the flange of the plug and said cover, arms on said plug adapted to pass through the slots and to ride up the cams onto the surfaces to compress the elastic washer against the cover, abutments adjacent said surfaces to prevent further rotative movement of the plug, and means to prevent the arms from being rotated away from said cams when in line with said slots.

In testimony whereof, I hereunto affix my signature:

C. W. HAZELETT.
